James W. Grandle

By Watson E. Coleman
Attorney

UNITED STATES PATENT OFFICE.

JAMES W. GRANDLE, OF PIERRE, SOUTH DAKOTA.

MITER GAUGE.

Application filed January 21, 1922. Serial No. 530,923.

To all whom it may concern:

Be it known that I, JAMES W. GRANDLE, a citizen of the United States, residing at Pierre, in the county of Hughes and State 5 of South Dakota, have invented certain new and useful Improvements in Miter Gauges, of which the following is a specification, reference being had to the accompanying drawings.

10 This invention relates to saw gauges and has for an important object thereof the provision of a gauge which may be employed for the formation of miter cuts or may be used for gauging a tool in gaining operations such as forming gains for shelving 15 and the like.

A further object of the invention is to provide a device of this character which is extremely simple in construction and 20 operation and which may be very cheaply constructed.

A still further object of the invention is to provide a neat and compact tool which may replace the ordinary miter box in making miter cuts and which may be much more readily employed.

Other objects and advantages of the invention will become apparent throughout the course of the following description.

30 In the accompanying drawings, wherein for the purpose of illustration is shown a preferred embodiment of my invention, and wherein like reference characters designate like parts throughout;

35 Figure 1 is a perspective view of a gauge constructed in accordance with my invention;

Figure 2 is a section on the line 2—2 of Figure 1;

40 Figure 3 is a section on the line 3—3 of Figure 1; and

Figure 4 is a section on the line 4—4 of Figure 1.

Referring now more particularly to the 45 drawings, my invention in its present embodiment consists in a main frame 10 comprising rectangularly disposed plates 11 and 12. The plate 11 is adapted to bear against the surface of the material to be cut at the 50 face thereof next adjacent that upon which the cut is to be made; is made entirely plain with the exception of openings 13 formed therein, through which securing elements may be driven into the member to be cut 55 to maintain the device in position. If de-

sired, the inner face of the plate 11 may have formed thereon piercing points 13^a for this purpose and the openings 13 may be dispensed with or both means may be employed.

The plate 12 has formed therein a longitudinally extending slot 14, the under sides of which will be under cut to form upon the under surface of the plate 12 rebated shoulders 15 having their faces milled. 60 Slidably mounted within the slot 14 is a runner 16 having at its sides flanges 17 operating beneath the shoulders 15 and having their upper surfaces milled. The upper surface of the runner 16 is substantially flush with the upper surface of the plate 12 and has secured thereto by means of a screw 18 extending into the runner a plate 19 which embodies portions overlying the edges of the slot 14. The plate 19 is 70 likewise secured at a point remote from the bolt 18 as at 20 to the runner so as to prevent shifting of the plate relative to the runner. This plate embodies a pointer finger 21 coacting with graduations 22 formed 80 upon the upper surface of the plate 12 at one side of the slot 14. The runner may be adjusted to any of the graduations and clamped in position, the screw 18 being provided with a clamping head 18^a.

The clamping head 18^a likewise serves to clamp one end of an arm 23 which surrounds the bolt 18 and is rotatable thereon. The plate 12 is provided at one end thereof with an enlargement 12^a having upstanding therefrom a pivot post 24.

The opposite end of the arm 23 is pivotally connected with a guide clamp C for guiding the saw in making the cut. This clamp consists of a pair of substantially 95 similar sections 25 having flat adjacent faces 26 which are smoothly finished and which are adapted to engage the opposite sides of a saw blade disposed therebetween. The faces 26 are held in engagement with the 100 saw blade interposed between by means of spring U-bolts 27 preferably two in number and disposed adjacent the ends of the sections 25. One of the sections 25 embodies an extension 28 disposed at the side thereof 105 remote from its plain face 26 and this extension is rotatably engaged with the post 24 of the plate 12, the extension being held in position thereon by means of a nut 29. This nut does not bind the extension 28, 110

since it engages against the shoulder 30 formed on the post 24. One of the U-bolts 27 preferably extends entirely through the sections 25 and is provided upon one leg 5 thereof with an extension 31 having its lower end arranged in the same plane as the under surface of the plate 12. The other leg of the U-bolt preferably forms the pivotal mounting of the arm 23 upon 10 the clamp. The inner edge of the plate 12 or that edge thereof most remote from the plate 11 is provided therein with a series of notches 32 and 32^a. The notches 32 are arranged at a predetermined distance from 15 one another, preferably approximately two inches and are designated by numerals to indicate the distance from the plate of a saw placed in the guide clamp C when the guide clamp is arranged at right angles 20 to the main frame 10.

A notch 32^a is arranged intermediate each of the notches 32 and is spaced therefrom a predetermined space, for example, three-quarters of an inch which is equivalent to 25 the thickness of a finished one-inch board such as employed in shelving. When it is desired to employ the device for miter cuts the face 11 is placed against the surface of the material to be cut next adjacent that surface 30 thereof where the miter cut is to be made and secured in position in any desired manner. A gauge may be then set to direct the clamp at the selected angle by loosening the thumb screw 18^a and shifting the pointer 21 35 of the plate 19 until it coincides with the graduations of the cut desired, the graduations 22 being marked in degrees, as 45°, 90°, etc. The 90° graduation is preferably arranged substantially centrally of the slot 40 14 as regards its length so that miter cuts may be made to either side of the center. The saw is then placed in position in the clamp and operated to form the cut.

When it is desired to employ the clamp for 45 gaining, as in forming a standard for shelving, a nail is driven into the material and the last right hand notch of the plate 12 engaged therewith. The cut is formed and the gauge is operated until the next notch 50 55 engages the nail when the second cut for the gain is made. These cuts may then be employed as guides in making succeeding cuts and the cuts may be spaced apart the desired distance by simply coinciding the notch at the desired measurement with the pre-

ceeding cut. Thus the gains may be spaced apart a distance of four notches, six, eight, or any other desired measurement within the scope of the instrument which may, of course, be made in any desired length. 60

From the foregoing, it is believed to be obvious that I have constructed an instrument for the purposes intended which is particularly well adapted for the use set forth in that it eliminates the necessity of providing separate instruments to perform the operations described, and in that it eliminates the necessity of employing miter boxes which are cumbersome and which after much usage become very inaccurate. It will 65 furthermore be obvious that many changes are possible in the shape, size and arrangement of the parts herein described without in any manner departing from the spirit of my invention, or the scope of the subjoined 70 claims. 75

What is claimed is:—

1. A device of the character described comprising an angle frame having formed in one plate thereof a longitudinally extending slot, a runner slidably mounted within the slot, a saw guide pivotally connected to said frame at one end thereof, an arm connecting the free end of the saw guide with said runner and pivotally connected with each 85 thereof, and means for simultaneously clamping the arm to the runner and the runner in adjusted position. 80

2. A gauge of the type described embodying a main frame comprising a pair of rectangularly disposed plates one of which is provided with a longitudinally extending slot, a runner slidably mounted in said slot and provided with a pointer coacting with the graduations formed upon the plate, 90 means for locking the runner in adjusted position, a clamp guide pivotally mounted upon the upper face of the slotted plate at one end thereof and embodying jaw sections, 95 spring U-bolts connecting said jaw sections and tending to force the same together, an arm pivotally connected to said runner at one end and with an arm of one of the U-bolts at the opposite end, and an extension carried by one of said jaw sections and having its lower face coplanar with the lower face of said plate. 100

In testimony whereof I hereunto affix my signature.

JAMES W. GRANDLE.
